H. A. ANDERSON ET AL.
IMPEDANCE BOND,
FILED JULY 29, 1922.

1,439,680.

UNITED STATES PATENT OFFICE.

HERMAN A. ANDERSON, OF PITTSBURGH, AND HARRY R. SMITH, OF WILKINSBURG, PENNSYLVANIA, ASSIGNORS TO THE UNION SWITCH & SIGNAL COMPANY, OF SWISSVALE, PENNSYLVANIA, A CORPORATION OF PENNSYLVANIA.

IMPEDANCE BOND.

Application filed July 29, 1922. Serial No. 578,385.

To all whom it may concern:

Be it known that we, HERMAN A. ANDERSON and HARRY R. SMITH, citizens of the United States, residing at Pittsburgh and 5 Wilkinsburg, respectively, in the county of Allegheny and State of Pennsylvania, have invented certain new and useful Improvements in Impedance Bonds, of which the following is a specification.

10 Our invention relates to impedance bonds, such for example as the bonds which are used in the trackway when an alternating current track circuit signaling system is applied to a railway both rails of which are 15 used for the transmission of propulsion current.

One object of our invention is the provision of novel and improved means for rigidly holding an impedance bond in place in 20 the case which encloses and protects it.

We will describe one form of an impedance bond embodying our invention and will then point out the novel features thereof in 25 claims.

25 In the accompanying drawing, Fig. 1 is a plan view, with cover removed, showing one form of bond embodying our invention. Fig. 2 is a vertical sectional view of the bond shown in Fig. 1. Fig. 3 is a fragmentary 30 plan view of the inside of the enclosing case shown in Figs. 1 and 2.

Similar reference characters refer to similar parts in each of the several views.

Referring to the drawing, the reference 35 character 10 designates an enclosing and protecting case which is usually of cast iron and is provided with a cover 10^a.

Located within this case is an impedance bond B, comprising a magnetizable core 13, 40 core plates 11 and 11^a for holding the laminated elements of the core together, and a winding 12 provided with terminals 19, 20 and 21 which project through suitable holes in the side of the case 10.

45 The bond B rests on lugs 15 which are cast in the bottom of the case 10, and is held in place in the case by the means which we will now describe.

Each end of each core plate 11 and 11^a is 50 provided with a projecting ear 17, and each ear has a round aperture 17^a designed to receive the shank of a bolt 16. It follows that

there are four such apertured ears at the four corners of the bond and near the top thereof, and four other such apertured ears 55 at the four corners of the bond and near the bottom thereof. The two apertures at each corner register with each other, and also registering with each pair of apertures are lugs 14, 14^a, 14^b and 14^c, which are cast in the bottom of the case 10. Each of these lugs is slotted, and by this we mean that the lug is provided with a groove having overhanging edges as shown in Figs. 2 and 3. These slotted lugs hold the squared heads of the bolts 60 16 and so prevent these bolts from being pulled upwardly. The bond is held down in the case by nuts 18 screwed onto the upper end of the bolts 16 above the top ear 17.

The slots in the two diametrically opposite lugs 14 and 14^b are parallel and are at right angles to the slots in the other two diametrically opposite lugs 14^a and 14^c, the slots in these last two mentioned lugs likewise being parallel. It will be seen from this arrangement that when the parts are in place and the nuts 18 are tightened it is impossible 70 for bond B to move horizontally in any direction in the case 10.

This structure has numerous advantageous features among which are the following: It accomplishes the desired result with the fewest possible number of parts, and owing to the fact that little or no fitting of the parts is necessary, it reduces the cost of assembling to the minimum. It provides the maximum opportunity for circulation of petrolatum or whatever other cooling medium may be contained in the case, because this medium is free to flow in all directions 80 around the core 13. It holds the bond positively in one position in the case, so that even if the structure is roughly handled the terminal devices 19, 20 and 21 will not be disturbed, as frequently happens when 85 the bond is capable of slight movement in the case. By this we mean that the case is sealed where these terminals are brought out and such seal is broken in the event of relative movement of the bond in the case. 90 95

Although we have herein shown and described only one form of bond embodying our invention, it is understood that various changes and modifications may be made 100

therein within the scope of the appended claims without departing from the spirit and scope of our invention.

Having thus described our invention, what we claim is:

- 5 1. In combination, a case provided with slotted lugs, an impedance bond located in said case and comprising apertured core plates, and bolts passing through the apertures in said core plates and having heads coacting with said slotted lugs.
- 10 2. In combination, a case provided with slotted lugs, the slots in certain of the lugs being at right angles to the slots in the other lugs, an impedance bond located in said case and comprising apertured core plates, and bolts passing through the apertures in said core plates and having heads coacting with said slotted lugs.
- 15 3. In combination, a case provided with slotted lugs, the slots in said lugs being disposed in different directions, an impedance bond located in said case and comprising apertured core plates, and bolts passing through the apertures in said core plates and having heads coacting with said slotted lugs.
- 20 4. In combination, a case the bottom of which is provided with four lugs, a slot in

each lug, each slot being provided with overhanging edges, the slots in diagonally opposite lugs being parallel and at right angles to the slots in the other diagonally opposite lugs, an impedance bond located in said case and including core plates provided with ears having apertures which register with said slotted lugs, and bolts passing through said apertures and having heads coacting with the slots in said lugs.

5. In combination, a case provided with four slotted lugs so disposed as to form a rectangle, the slots in each two diagonally opposite lugs being parallel and at right angles to the slots in the other two diagonally opposite lugs, an impedance bond located in said case and comprising two core plates each having apertures which register with the lugs in the case, four bolts, one for each lug, and each having a head coacting with the associated lug and a shank passing through the corresponding apertures in the core plates, and nuts coacting with said bolts to hold the bond in place in the case.

In testimony whereof we affix our signatures.

HERMAN A. ANDERSON.
HARRY R. SMITH.
